[57] CLAIM

The ornamental design for a beverage dispenser, as shown.

DESCRIPTION

FIG. 1 is a top, front right side perspective view of a beverage dispenser showing our new design;
FIG. 2 is a right side elevational view thereof;
FIG. 3 is a left side elevational view thereof;
FIG. 4 is a front elevational view thereof;
FIG. 5 is a top plan view thereof;
FIG. 6 is a rear elevational view thereof;
FIG. 7 is a bottom plan view thereof;
FIG. 8 is a top, front, right perspective view of a beverage dispenser showing a second embodiment of our new design;
FIG. 9 is a front elevational view thereof;
FIG. 10 is a rear elevational view thereof;
FIG. 11 is a left side view thereof;
FIG. 12 is a right side view thereof;
FIG. 13 is a top plan view thereof; and,
FIG. 14 is a bottom plan view thereof.

The broken line showing four cups in FIG. 8 is for illustrative purposes only and forms no part of the claimed design.
